DYE JIG

Fred Kenyon, Bradford, R. I., assignor to B. F. Perkins & Son, Inc., Chicopee, Mass., a corporation of Massachusetts

Application July 20, 1937, Serial No. 154,591

5 Claims. (Cl. 68—180)

This invention relates to improvements in apparatus for dyeing webs of material such as cloth or to improvements in a machine commonly called a dye jig.

The principal objects of the invention are directed to the provision of a novel dye jig which is characterized by its simplicity of form and its efficiency in operation. By means of the dye jig of the invention it is possible, without intricate mechanism, to obtain a constant speed which is very important. There is produced a dyed web, such as of fabric, which is without dark selvages and there is also a level dyeing from one end to the other end of the batch. According to this invention, the dye jig operates with a minimum of streaks, and it is adapted for various dyeing operations on all materials such as rayon and celanese. The dyeing operation is considerably quicker than with dye jigs heretofore known without an injurious tension being applied to the web being dyed.

Various novel features and advantages of the invention will be hereinafter more fully referred to in connection with the accompanying description of the preferred form of the invention, and it will be understood that various changes and modifications may be made without departing from the spirit and scope of the invention.

In the drawing

Fig. 1 is a side elevational view, with some parts in section, of a dye jig embodying the novel features of the invention;

Fig. 2 is a partial transverse sectional elevational view taken at one end of one of the winding mechanisms of the machine; and

Fig. 3 is a small scale diagrammatic view to explain the various driving connections of the machine shown in Fig. 1.

Referring now to the drawing in detail, the invention will be more fully described. The machine includes side frames such as 2 which may be tied together and held apart in spaced relation by transverse members such as 4. The said frames are adapted to rest on the floor F or upon a foundation if desired.

Between the frames 2 there is a pan or vat 6 which inclines downwardly from its ends, as shown, to a depressed portion or sump 8 which may be supported on a transverse member 10. Through the depressed portion there may be one or more runs of pipe indicated by 12 into which steam or some other heating medium may be introduced. For purposes of heating the dye material contained in the sump and for some other pur-

poses it is desired to have one or more pipes such as 14 in the sump portion which receive steam and is slit or perforated so as to deliver steam into the dyeing material. The amount of steam admitted to the pipes may be varied by means of valves in the well-known manner. The web of material to be dyed is preferably handled in roll form and the web from a roll of material at one end of the machine is unwound and passed thru and wound up at the other end. For instance, the web W from roll 16 passes between upper and lower rollers 18 and 20, over guides 22, 24, 26, 28, 30, 32, 34, between rolls 36 and 38 and is wound up in a roll 40. It may be assumed for purposes of description that the web is unrolled from the roll at the left of the machine, passed through the machine and rolled up again at the right of the machine.

If it is desired the web may pass through the machine in an opposite direction, or it may be passed through in one direction and returned through the machine in an opposite direction. The rolls 18, 20, 36 and 38 have their shafts journaled in boxes such as 42, 42', 46 and 46' which are slidable up and down in standards 50 and 52. There are two standards 50 which are spaced apart at one end of the machine and there are other spaced apart standards 52 at the other end thereof.

The lower boxes 42' and 46' rest in the bottoms of vertical guideways of the standards as shown. The upper boxes may move up and down in the standards so that the upper rolls may rest on the lower ones or are urged thereagainst by means of springs 54. Plates 56 which are slidable in the standards are moved up and down by screws 58 which are in engagement with nuts 60 which are rotatable in caps 62 and they are rotated by worm gears 64 as shown. Transverse shafts 66 carry worms 68 in mesh with gears 64. By rotating the shafts, the plates 56 are moved up and down to tension the springs 54. In this way the springs offer various degrees of resistance to upward movements of the boxes and the upper rolls carried thereby so that the pressure is variable. The rolls 20 and 38 are operatively connected so that they rotate in timed relation relative to one another and to that end the shafts thereof carry sprockets 70 and 72 which are connected by a chain 74, (see Fig. 3). The roll 20 may be the driving element and to that end a motor 76 has a sprocket 78 and a chain 80 passes over that sprocket 78 and another sprocket 82 associated with the roll 38.

Arbors or spindles are provided for the rolled up web at either end of the machine, one for the roll being unrolled and the other for the roll being rolled up. These arbors are driven in such a way as to feed the web through the machine without exerting undue tension thereon or without permitting the web to become unduly slack.

Brackets 90 extend outwardly from the machine side frames and to these transversely-extending brackets 92 are secured. Shafts 94 are rotatable in the brackets 92. Friction disks 96 are keyed to the shafts 94, and on their hubs there are rotatable, friction disks 98 (see Fig. 2). Movable disks 100 are slidable on the hubs of disks 96 but are non-rotatable thereon. Friction members 102 and 104 are provided between the members 100 and 96 and between 98 and 96. Sleeve members 106 are secured to brackets 92 and have in screw threaded relation therewith nuts 108 in the form of handwheels and similar handwheels 110. The devices 108 may be screwed along the threaded member 106 to exert endwise pressure against the member 100 and it may be locked in position by the member 110. By means of the mechanism just described, it is possible to exert more or less end-wise pressure so as to produce various frictional effects. The rolls 20 and 38 have attached thereto sprockets 112 and 114 engaging chains 116 and 118 which pass around sprockets such as 120 and which are fixed to the intermediate member 98.

As 20 and 38 are rotated the intermediate members as 98 are rotated thereby and the shafts 94 are driven through the frictional mechanism. It will be apparent that there may be more or less slip or frictional action between what may be called the drivers 98 and the shafts 94 so that the web may be fed through the machine in the desired manner.

Each shaft 94 has associated therewith a drum 126 which is adapted to receive the end of a winding arbor or shaft for the rolled up web and which is indicated by 128. A band 130 in frictional engagement with the drum is secured to the bracket 92 and 122 and is adjustable at 134. The band resists rotation of the shaft due to the frictional action between the band and the drum.

The rolled up web to be dyed is fed through the machine as from left to right or from right to left as may be desired. It may be led therethrough in one direction for a dyeing operation and reversed and led therethrough in an opposite direction all as may be desired and the tension may be regulated within wide limits so that the web is not strained to an injurious extent but yet is positively fed so as to produce the desired results.

It will be noted that the tension of the web may be varied and that the frictional mechanism provides variation within wide limits for driving the arbor for the roll which cooperates with the frictional drum mechanism so as to provide wide range of flexibility all to the end that the machine is capable of many and various uses where it is desired to perform various operations on webs of all kinds.

Having described the invention in the present preferred form thereof and since many changes and modifications may be made without departing from the spirit and scope of the invention, what I desire to claim and secure by Letters Patents of the United States is:

1. A machine of the class described comprising in combination, a frame work having sup-

ports at opposite ends thereof and a tank therebetween, pairs of coacting rolls disposed above each end of said tank, mountings for each pair of rolls associated with the said supports arranged and adapted for rotatably supporting the rolls of each pair with the peripheries thereof in yielding engagement, a plurality of guide rolls disposed for rotation in said tank and between and below said pairs of rolls, driving connections between a certain of the rolls of each pair of rolls, driving means for said machine connected to one of said certain rolls, arbors rotatably mounted at each end of said machine, and driving connections between said certain rolls and said arbors including variable friction devices, all adapted and arranged whereby a web may be unwound from a roll on either one of said arbors, passed between the pair of rolls adjacent said one arbor around said guide rolls downwardly into, across and upwardly of said tank and outwardly between the other pair of rolls and rewound on the other of said arbors.

2. A machine of the class described comprising in combination, a frame work having supports spaced apart and disposed at opposite ends thereof and a tank therebetween, pairs of coacting rolls disposed above each end of said tank, mountings for each pair of rolls associated with said supports arranged and adapted for rotatably supporting said rolls of each pair with the peripheries thereof in yielding engagement, spaced apart guide rolls disposed for rotation in said tank and between and below said pairs of rolls, driving connections between a certain of the rolls of each of said pairs of rolls, driving means for said machine connected to one of said certain rolls, arbors rotatably mounted at each end of said machine, and driving connections between said certain rolls and said arbors including variable friction devices, all adapted and arranged whereby a web may be unwound from a roll on either one of said arbors, passed between the pair of rolls adjacent said one arbor beneath and around said guide rolls downwardly into, across and upwardly of said tank and outwardly between the other pair of rolls and rewound on the other of said arbors, and variable means associated with each of said arbors for resisting rotation of said arbors.

3. A machine of the class described comprising in combination, a frame work having supports spaced apart and disposed at opposite ends thereof and a tank therebetween, pairs of coacting rolls disposed above each end of said tank, mountings for each pair of rolls associated with said supports arranged and adapted for rotatably supporting said rolls of each pair with the peripheries thereof in yielding engagement, spaced apart guide rolls disposed for rotation in said tank and between and below said pairs of rolls, driving connections between a certain of the rolls of each pair of rolls, driving means for said machine connected to one of said certain rolls, arbor shafts mounted for rotation in said frame work outside each pair of rolls, means for driving said arbor shafts from said certain rolls including a friction member fixed to each of said shafts and a member frictionally engageable therewith rotatable relative thereto, driving connections between each of said last named members and said certain rolls, and variable means to urge said friction members into operative engagement, all adapted and arranged whereby either one of said arbor shafts may be driven by

the certain roll to which it is connected and to said shaft, an arbor connected to said one shaft may rewind a web unwound from an arbor connected to the other of said shafts and passed successively between one pair of rolls, over said guide rolls and through said tank and outwardly between the other pair of rolls.

4. A machine of the class described comprising in combination, a frame work having supports at opposite ends thereof and a tank therebetween, pairs of coacting rolls disposed above each end of said tank, mountings for each pair of rolls associated with the said supports arranged and adapted for rotatably supporting the rolls of each pair with the peripheries thereof in yielding engagement, a plurality of guide rolls disposed for rotation in said tank and between and below said pairs of rolls, driving connections between a certain of the rolls of each pair of rolls, driving means for said machine connected to one of said certain rolls, arbor shafts mounted for rotation in said frame work outside each pair of rolls, an arbor for each shaft, frictionally engageable means associated with said arbors, a driven friction member fixed to each of said shafts, driving friction members rotatable relative to the driven members, driving connections between said driving members and said certain rolls, and variable means for urging said friction members into engagement, said frictionally engaging means including, drums rotatable with

said shafts and arbors and adjustable bands acting thereon.

5. A machine of the class described comprising in combination, a frame work having supports spaced apart and disposed at opposite ends thereof and a tank therebetween, pairs of coacting rolls disposed above each end of said tank, mountings for each pair of rolls associated with the said supports arranged and adapted for rotatably supporting the rolls of each pair with the peripheries thereof in yielding engagement, a plurality of guide rolls disposed for rotation in said tank and between and below said pairs of rolls, driving connections between a certain of the rolls of each pair of rolls, driving means for said machine connected to one of said certain rolls, arbor shafts mounted for rotation in said frame work outside each pair of rolls, an arbor for each shaft, driving and driven frictionally engageable members associated with said shafts and arbors, variable means for urging said members into frictional engagement, variable friction means associated with said arbors and frame work, and driving connections between said driving members and said certain rolls, said variable friction means including, drums rotatable with said shafts and arbors and adjustable bands on said frame work acting thereon adapted to resist rotation of said arbors.
